COMBINED MOTION PICTURE PROJECTOR AND
CARRYING CASE OR SIMILAR ARTICLE

Otto R. Nemeth, Los Angeles, Calif., assignor to
Sawyer's Inc., a corporation of Oregon

Filed May 5, 1966, Ser. No. 2,172

Term of patent 14 years

(Cl. D61—1)

Fig.1.

Fig.2.

Fig.3.

Fig.4.

Fig.5.

FIG.6.

FIG.7.

FIG.8.

FIG.9.

FIGURE 1 is a rear, top and left side perspective view of a combined motion picture projector and carrying case or similar article, showing my new design with the cover on;

FIGURE 2 is a right side elevational view with the cover on;

FIGURE 3 is a rear elevational view with the cover on;

FIGURE 4 is a top plan view with the cover on;

FIGURE 5 is a bottom plan view with the cover on;

FIGURE 6 is a left side elevational view with the cover removed;

FIGURE 7 is a front elevational view with the cover removed;

FIGURE 8 is a rear elevational view with the cover removed; and,

FIGURE 9 is a top plan view thereof with the cover removed.

I claim:

The ornamental design for a combined motion picture projector and carrying case or similar article, substantially as shown.
